(57) **CLAIM**

The ornamental design for a glass cup, as shown and described.

DESCRIPTION

FIG. 1 is a top perspective view of a glass cup, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a sectional view of 9-9 along the line in FIG. 3;

FIG. 10 is a sectional perspective view of 10-10 along the line in FIG. 3; and,

FIG. 11 is a partial enlarged view of FIG. 8.

The dash-dot-dash broken lines are for notating enlarged views, and form no part of the claim design.

1 Claim, 11 Drawing Sheets
